FUSE-CARRYING CONNECTING DEVICE FOR ELECTRICAL CONDUCTORS.

1,153,657.

Specification of Letters Patent. Patented Sept. 14, 1915.

Application filed October 12, 1914. Serial No. 866,235.

To all whom it may concern:

Be it known that I, FREDERICK N. WAKE, a citizen of the United States of America, residing in the borough of the Bronx, city of New York, county of Bronx, State of New York, have invented a new and useful Improvement in Fuse-Carrying Connecting Devices for Electrical Conductors, of which the following is a specification.

- 10 This invention has for its object to provide a simple and efficient electric line wire connector carrying an internal safety fuse and adapted for coupling ends of line wire sections by use of ordinary contact clamps and without using solder, and also permitting quick and convenient renewal of the fuse without injury to the connector casing or fuse plugs or to the end caps to which the line wire clamps are attached.
- 15 20 The invention consists in a fuse connector device comprising a casing, removable end plugs in the casing, a fuse connected in circuit with opposite end plugs, and removable end caps simultaneously engaging the plugs and the casing and adapted for electrical connection with attachments to the line wire sections. Means also are provided for preventing independent turning of the plugs in the casing when they have screw-connection with the end caps while the caps have screw-connection with the casing, and said detent means are arranged also to preferably relieve the fuse of endwise pressure when opposing contacts are forced together. The
- 25 30 35 40 45 50 end caps also may be in two parts comprising a body or ferrule removably fitted to the casing and a head or disk portion relatively movable on the ferrule, as by a screw connection therewith, and forming a contact which thus may be forced into intimate electrical connection with the opposed fuse-carrying plug contact. The fuse also preferably has readily detachable connections at opposite ends with the opposite end contact plugs of the device. A gas generating substance also is provided in the fuse chamber to smother or extinguish the electric arc flame should the fuse be burned out, all as hereinafter described and claimed.
- 50 In the accompanying drawings: Figure 1 is a longitudinal sectional elevation of an improved connector: Fig. 2, an end view

thereof with the screw cap removed: Fig. 3, a sectional view showing the end cap formed with relatively adjustable ferrule and disk 55 portions: Fig. 4, a perspective view of the connector with the fuse-carrying contact plug and one end cap removed: Fig. 5, a perspective view of a preferred key device which holds the fuse plug nonrevolvably to 60 the connector casing: Fig. 6, a perspective view of one of the fuse plugs: Fig. 7, a side elevation of the fuse with one of its end heads in section.

Referring first more particularly to Figs. 65 1, 2, 4, 5, 6, 7, of the drawings, the numeral 1, indicates the fuse which preferably has fixed opposite end heads, 2, 3, each having and external screwthread 4 adapted to engage threads formed in the inner parts of the two 70 opposite contact plugs 5, 6. Each of these plugs has near its outer and preferably tapered end two oppositely disposed transverse slots 7, 8 receiving opposite limbs 9, 10 of a U-shaped key device 11. This key 75 enters transverse end notches 12 made in the connector casing 13 and the key limbs abut end shoulders 14 of said notches whereby the key prevents the plug 5 or 6 from turning in the casing when a central externally 80 threaded stud 15 fixed to the end wall of the cap 16 is screwed into internal threads 17 of the plug while an internal thread of the cap screws upon an external thread 18 formed on the casing 13. Said key device 85 90 may have any other form serving its intended purposes. It will be understood that the plugs 5, 6 are first screwed upon the end heads 2, 3 of the fuse 1, and that the united parts 1, 2, 3, 5, 6 are then slipped into the 95 casing and the keys 11 then are entered into the plug slots 7, 8 and casing notches 12 so that the opposite ends of the keys then lie within the bases of the casing threads 18 to permit the caps 16 to make the above named 95 screw connections with the plugs and the casing, the threads of the plugs and caps being properly proportioned to allow their above named screw engagement. The keys 11 thus lock the fuse-carrying plugs 5, 6 100 nonrevolvably in the connector casing 13 and permit quick and positive simultaneous screw connection of the caps 16 to both the plugs and the casing, and, as the caps are

screwed home to make reliable electrical contact between them and the plugs and the fuse, the keys 11 by supporting the fuse plugs 5, 6 in the casing notches 12, entirely relieve the fuse itself of any damaging endwise pressure as the opposing contacts are forced together. Any suitable flame-suffocating powder or compound 19 may be filled into the casing 13 around the fuse 1 to extinguish the arc should the fuse be burned out by excessive electric current. After the direct line clamps (not shown) are removed from the end caps 16, the latter may be unscrewed thereby exposing the fuse plugs and keys. The plugs 5, 6 and the keys 11 then are slipped from the casing to allow substitution for a burnt out fuse of a new fuse which may quickly and easily be done by unscrewing the old fuse heads 2, 3 from the plugs 5, 6 and screwing the plugs upon the heads 2, 3 of a new fuse, and then inserting the connected fuse and plugs into the casing 13 and applying the keys 11 and finally screwing the cap studs 15 into the plugs while the caps screw upon the casing, and all without using soldered joints between the casing and the caps or between the fuse and the connected plugs or between the line wires and the casing. Electrical circuit is formed through the wire-connected clamps to the end caps 16, the plugs 5, 6 and the fuse heads 2, 3 to and through the fuse 1.

In the desirable construction shown in Fig. 3 of the drawings, the end cap is formed of a clamp-connecting tubular body or ferrule portion 20 internally threaded at 21 for its whole length and a separate head or disk portion 22 externally threaded to engage the ferrule threads 21. The stud 15 is here fixed to the disk 22 which at any time may be screwed inward to force it into intimate unvarying electrical contact with the adjacent key-sustained fuse contact plug 5 or 6 and without detaching or in any way disturbing the electric line wire connections with the cap ferrule 20 and while the fuse 1 is held under proper tension and is relieved by the key 11 from damaging endwise pressure. Fig. 3 also shows that instead of using a granular arc-smothering substance 19 in the casing 13 (as shown in Fig. 1), the fuse itself may be coated or covered by a paste composition 23 which, in presence of the heat developed by burning out of the fuse, will produce a gas that acts to extinguish the arc. An example of such a composition is as follows:—Portland cement, 1 part; calcium bicarbonate, 8 parts; borax, 4 parts; asbestos powder, 4 parts. This composition in or about the proportions stated, and in either the form of the paste 23 applied directly to the fuse or in the form of a powder filled into the casing chamber around the fuse, has been shown by experi-

ment to be efficient in use. When the fuse burns out, carbonic acid gas is generated from the powder 19 or paste 23 in the casing fuse chamber and acts to smother the flame of the arc.

Should ventilation of the connector casing 13 be desirable or necessary, one or more small ventilating holes or slots 24 may be made in the casing.

In all above described forms of this improved connector device the electrical engagement of all contacts is unvarying and positive and therefore the device is not subject to change or disorganization in use and it may be made at low cost and sold at a reasonable price. Furthermore, the construction permits use of connector casings 13 and end caps thereon of any prescribed standard necessary lengths or dimensions, and all parts are interchangeable thereby promoting cheap original manufacture and easy subsequent repair of all parts of the connector device.

I claim:

1. A fuse connector device comprising a casing having external end threads and end notches, removable end plugs in the casing having oppositely disposed transverse slots and a central internally threaded aperture, a fuse connected in circuit with opposite end plugs, keys entering the casing notches and plug slots and preventing independent turning of the plugs in the casing, and end contact caps having internal threads fitting the casing threads, each end cap also having an externally threaded central stud adapted to the internally threaded aperture of the corresponding plug, substantially as described.

2. A fuse connector device comprising a casing having external end threads and end notches, removable end plugs in the casing having oppositely disposed transverse slots and a central internally threaded aperture, a fuse connected in circuit with opposite end plugs, keys entering the casing notches and plug slots and preventing independent turning of the plugs in the casing and relieving the fuse of endwise pressure when opposing contacts are forced together, and end contact caps having internal threads fitting the casing threads and an externally threaded central stud adapted to the internally threaded aperture of the corresponding plug, substantially as described.

3. A fuse connector comprising a casing, end plugs therein, a fuse connected in circuit with opposite end plugs, said casing having end notches and the plugs having opposite transverse peripheral slots, U-shaped one-piece key devices having key limbs entering the casing notches and plug slots and preventing independent turning of the plugs in the casing and removable end contact caps simultaneously engaging the plugs

and the casing and adapted for electrical connection with attachments to line wire sections, substantially as described.

4. A fuse connector device comprising a casing, end plugs therein, a fuse connected in circuit with opposite end plugs, said casing having end notches and the plugs having opposite transverse peripheral slots, U-shaped one-piece key devices having key limbs entering the casing notches and plug slots and preventing independent turning of the plugs in the casing and relieving the

fuse of endwise pressure when opposing contacts are forced together, and removable end contact caps simultaneously engaging the plugs and the casing and adapted for electrical connection with attachments to line wire sections, substantially as described. 15

In testimony whereof, I have hereunto subscribed my name.

FREDERICK N. WAKE.
